UNITED STATES PATENT OFFICE.

JOHN SCHEIBLING, OF NEW YORK, N. Y.

COIN-CONTROLLED GARMENT-HOOK.

SPECIFICATION forming part of Letters Patent No. 729,900, dated June 2, 1903.

Application filed February 7, 1903. Serial No. 142,260. (No model.)

To all whom it may concern:

Be it known that I, JOHN SCHEIBLING, a citizen of the United States, residing at New York city, (Manhattan,) county and State of New York, have invented certain new and useful Improvements in Coin-Controlled Garment-Hooks, of which the following is a specification.

This invention relates to an improved coin-controlled garment-hook which is so constructed that by first introducing a coin into the coin-drop of the casing containing the hook its door is unlocked, the key is delivered, and the coin-drop is closed. The garments are then suspended upon the hooks and the door is closed. By subsequently introducing the key into the key-drop the door is unlocked for the removal of the garments and the coin-drop is reopened, ready for the next operation.

In the accompanying drawings, Figure 1 is a perspective view of my improved coin-controlled garment-hook; Fig. 2, a front elevation of the same, showing the coin-pocket open; Fig. 3, a front view of the operating mechanism with the coin-pocket closed; Fig. 4, a vertical cross-section on line 4-4, Fig. 3; Fig. 5, a horizontal section on line 5-5, Fig. 4. Figs. 6 and 7 are details of the coin-drop, showing it in different positions. Figs. 8 and 9 are corresponding views of the key-drop. Fig. 10 is a plan of the key-ejector, and Fig. 11 a detail of the slotted coin-supporter.

The letter A represents the casing of the apparatus, that incloses or controls access to the hooks or other devices for holding garments, hats, umbrellas, or canes. Thus the drawings show the casing to contain a coat-hook a , an umbrella or cane clasp a' , and a hat-holder a'' , over which is adapted to be projected a locking-arm a^3 , secured to the hinged door A' of casing A. The door A' is provided with a coin-slot A^2 and a key-slot A^3 . The slot A^2 delivers the coin by chute a^4 , Figs. 6 and 7, into a pocket b , which is open at its bottom and placed above a transverse shaft c , hung within casing A. Upon shaft c are mounted, directly beneath pocket b , a pair of radially-slotted disks c' , Fig. 11. Thus when the slots c^2 of disks c' are brought into alignment with the pocket the coin B within the latter will fall through the same

and into engagement with the slotted disks c' , so as to participate in their movement. To operate the shaft c , it projects at one end 55 through casing A, and is here provided with a knob c^3 , which permits the shaft c to be rotated backward only, a rotation in the opposite direction being prevented by a pawl c^4 and ratchet-wheel c^5 .

The mechanism described is duplicated in all material respects for causing the engagement of a key D, which is dropped through slot A^3 with the shaft c —that is to say, a chute a^5 on door A' , back of slot A^3 , Figs. 8 and 9, 65 delivers the key to an open pocket d , arranged alongside of pocket b directly above shaft c . Beneath the pocket d the shaft c carries the disks c^6 , slotted at c^7 , so that the key falling through the pocket will drop into the 70 slots c^7 as soon as the latter are brought into alignment with the pocket.

The pockets b and d are each provided with means for closing the mouths of the same, the construction being such that when the 75 pocket b is opened for the admission of the coin the pocket d is closed against the admission of the key, and vice versa. To effect this result, I fulcrum at e' , midway between the pockets b d , a two-armed lever or beam e , carrying on each arm a locking-pin e^2 and e^3 . The rear walls $b' d'$ of pockets b d are slotted vertically, as at $b^2 d^2$, for the reception of the pins $e^2 e^3$, respectively. In this way when one of the beam-arms is lowered its pin will 80 project across the mouth of the pocket to close the same, while the pin on the raised beam-arm will leave the other pocket open.

The coin B, which is taken along by the slotted disk c' of shaft c as the latter is turned 90 backward by its knob c^3 , has to perform three functions: First, it unlocks the door A' ; secondly, it closes the mouth of the coin-pocket, and, thirdly, it ejects the key from the casing.

Normally the door is locked by the engagement of a catch f on the door with a hook f' , pivoted within the casing at f^2 and constituting a latch. Across the lower side of this hook extends a lifting-bar g , connected at each end to a lever g' and g^2 , turning on a 95 common pivot g^3 . The lever g' is arranged between the disks c' , so as to be in the path of the coin held thereby, while the lever g^2 is arranged between the disks c^6 , so as to be in

the path of the key. Thus when either of the levers g' g^2 is swung upward the door will be unlocked. When the coin or the key has cleared the lever g' or g^2 , respectively, the lifter g , as well as the hook f' , will descend to its normal position by gravity.

Within the path of coin B—i. e., between the disks c' —is also arranged the lower end of a lever h , fulcrumed at h' and projecting with its upper end over that end of beam e which extends along the coin-pocket b . When the coin B, held by the disks c' , engages lever h , the upper end of such lever will bear upon beam e , so as to lower pin e^2 and raise pin e^3 , Figs. 6 and 8. Consequently pocket b will be closed and pocket d will be opened in the manner above described. A lever i is also arranged in the path of coin B between disks c' . This lever is fulcrumed at i' at its upper end, while its lower end engages and actuates a slide j , Fig. 10, pivoted at j' and influenced by a spring j^2 . The slide j carries at its free end a bottomless key-holding cup j^3 , which is normally closed by a fixed bed-plate k and is arranged beneath the key-disks c^6 . This plate has an opening k' , through which the key in cup j^3 will drop as soon as the cup is swung into vertical alinement with the opening. The coin by bearing against lever i will swing slide j in the manner described across the opening k' , and thus release the key. After the coin has cleared the lever i the slide j will be returned to its normal position by spring j^2 , so that the cup j^3 is again closed. The key when released from the cup in the manner described will fall into a chute k^2 , which delivers it to a tray k^3 . This tray projects outward beyond door A' and presents the key to the operator.

When the coin held by disks c' has performed its functions above enumerated and the slots c' are inclined with their open ends downward, the coin will become unseated and fall into a locked drawer 1 from which it may be removed.

The key D, when carried along by the disks c^6 of shaft c , has to perform two functions: First, it unlocks the door A' , which is effected by means of the lever g^2 , that raises hook f' through lifter g , as already described; secondly, the coin swings the beam e in order to unlock the coin-pocket b and relock the key-pocket d . This result is accomplished by a lever m , arranged between disks c^6 in the path of the key D. The lever m is constructed in all respects similar to lever h and is adapted to bear upon that end of beam e which extends along the key-pocket d . When the key bears against lever m , the upper end of such lever will depress beam e to lower pin e^3 and raise pin e^2 , Figs. 9 and 7. The key when unseated from disks c^6 drops into the cup j^3 , Fig. 8, ready for the next operation.

In use the coin is dropped into slot A^2 and will fall through the drop, composed of chute a^4 and open pocket b , so as to rest upon the edges of the disks c' , Fig. 2. The shaft c be-

ing now partly rotated by knob c^3 will first carry the slots c^2 into alinement with pocket b to receive the coin and will then carry the entrapped coin into engagement with the three levers g' , h , and i . These levers will, as already stated, respectively unlock the door A' , close pocket b , and deliver the key D to the tray k^3 . The operator may now open the door A' , pocket the key, and suspend the garments, &c., upon the supports a a' a^2 . When the operator desires to put on his coat, he drops the key D into the slot A^2 , so as to fall through chute a^5 and open pocket d , constituting the key-drop, upon the edges of the disks c^6 . The shaft c , being again partly rotated by knob c^3 , will first carry the slots c^7 into alinement with pocket d , will then carry the entrapped key into engagement with the levers g^2 and m , and will then pass the key to the cup j^3 , Fig. 8. This will first unlock the door A' and will then open the pocket b and close pocket d . After the garments have been removed the door is relocked and the apparatus is in position for the next manipulation.

Of course the coin-slot and the key-slot must be of different size or configuration, so as to exclude the key from the coin-slot, and vice versa.

It is necessary to have the pocket b closed by pin e^2 after the introduction of the coin to prevent the subsequent opening of the door by a coin instead of by a key. The closing of the key-pocket is not absolutely necessary, and the pin e^3 may in some cases be dispensed with.

What I claim is—

1. A coin-controlled garment-hook provided with a casing, a coin-chute, a key-chute, a rotatable shaft, means on said shaft adapted to receive a coin and key, respectively, a latch, and levers in the path of the coin and key, respectively, that are adapted to operate said latch, substantially as specified. 105

2. A coin-controlled garment-hook provided with a casing, a coin-chute, a key-chute, a rotatable shaft, slotted disks mounted thereon and adapted to receive the coin and key, respectively, a latch, and levers in the path of the coin and key, respectively, that are adapted to operate said latch, substantially as specified. 115

3. A coin-controlled garment-hook provided with a casing, a coin-chute, an open coin-pocket, a key-chute, an open key-pocket, a rotatable shaft, slotted disks mounted thereon beneath the pockets, a latch, and levers in the path of the coin and key, respectively, that are adapted to operate said latch, substantially as specified. 120

4. A coin-controlled garment-hook provided with a casing, an open coin-pocket, an open key-pocket, a beam fulcrumed intermediate said pockets, a pin on the beam adapted to close the coin-pocket upon the tilting of the beam in one direction, a rotatable shaft beneath the pockets, means on said 130

shaft adapted to receive a coin and key, respectively, and levers in the path of the coin and key which are adapted to tilt the beam, substantially as specified.

- 5 5. A coin - controlled garment - hook provided with a casing, an open coin-pocket, an open key-pocket, a rotatable shaft beneath the pockets, disks on said shaft adapted to receive a coin and key, respectively, a lever in the path of the coin, a slideable bottomless cup beneath the key-disk into which the key is adapted to be passed from said disk, and a perforated bed-plate beneath the cup, substantially as specified.
- 10 6. A coin - controlled garment - hook provided with a casing, a coin - pocket, a key-pocket, a rotatable shaft beneath the pockets,

means on said shaft adapted to receive a coin and key, respectively, a latch, levers in the path of the coin and key for releasing said latch, 20 a pin for closing the coin-pocket, a lever in the path of the coin adapted to operate said pin, a slideable key-cup beneath the key-receiving means on the shaft, and a lever in the path of the coin adapted to actuate said cup, 25 substantially as specified.

Signed by me at New York city, (Manhattan,) New York, this 6th day of February, 1903.

JOHN SCHEIBLING.
